UNITED STATES PATENT OFFICE.

WILLIAM H. PETERS, OF HOQUIAM, WASHINGTON, ASSIGNOR TO EDWARD A. BALDWIN, OF PORTLAND, OREGON.

WRENCH.

SPECIFICATION forming part of Letters Patent No. 674,814, dated May 21, 1901.

Application filed December 15, 1899. Serial No. 740,457. (No model.)

To all whom it may concern:

Be it known that I, WILLIAM H. PETERS, a citizen of the United States, and a resident of Hoquiam, Chehalis county, and State of Washington, have invented a new and useful Automatic Wrench, of which the following is a specification, reference being had to the accompanying drawings as a part thereof.

My invention relates to wrenches or spanners of the monkey-wrench type; and the object of my invention is to obtain an article of manufacture which will be automatic or self-adjusting in its operation. To accomplish this, the lower or inner jaw of my wrench is slidably mounted on the upper part of the shank. Said shank is composed of two jointed parts, the lower of which acts as a lever, and a link or member connects such lever part with the movable jaw and moves the latter against or from the fixed outer or upper jaw responsive to the manipulation of the wrench. Thus all that is required in using my wrench is to lift the head, so as to open or spread the jaws, which may then be placed on the nut to be turned, and by now manipulating the wrench in the usual way the jaws are closed upon the nut, the force with which the jaws grip or hold the nut being proportionate to the force required to turn the nut. Of course the wrench must be so adjusted that the lever part of the shank will be operated against the direction of resistance of the nut or object being held.

My invention may be cheaply and strongly made, consisting of but few parts, all of which will be more clearly understood from the drawings and description thereof hereinafter given.

In the drawings, Figure 1 is an elevation of my wrench, showing the same as about applied to a nut and the dotted lines showing the lever part of the shank and handle as moved in the direction in which the nut designated by N is to be forced. Fig. 2 is a front end elevation. Fig. 3 is a detail in perspective of the movable jaw. Fig. 4 is a similar detail of the link or member d, and Figs. 5 and 6 are details showing means for holding the heads or ends of the link d against falling out of their sockets or recesses in the lug c and movable jaw.

Like letters refer to like parts in both the drawings and description thereof.

Referring to the drawings, the outer jaw a is rigidly fixed on the head of the shank b. 55 The shank consists of two jointed parts, the lower, of which, b', is adapted to operate as a lever. To form the joint uniting the two portions of the shank, the lower end b² of the upper portion of the shank is reduced, the head of the lower portion b' is forked at b³ to receive the reduced part b², and a rivet b⁴ holds the parts together. Projecting laterally from the lever b' is a lug c, having an annular recess or socket on the upper side, the lug c 65 projecting at an acute angle with respect to the portion or member b', so as to be adapted to the operations of the link d, as illustrated in Fig. 1. The upper portion of the shank may be of quadrangular form, and on this 70 portion of the shank is slidably mounted a movable jaw a', having an aperture corresponding to this form of the shank. On the under side of the movable jaw a' is also provided an annular recess or socket. 75

d is a link having rounded heads or ends, which are inserted in the recesses or sockets in the lug c and the movable jaw. To keep the link from falling out of place, the lower head or end may be provided with a groove, like d', 80 to receive a set-screw e for that purpose provided in the lug c, or else the rim or verge of either of the recesses in the movable jaw or lug c, or both, may be slightly spread, by means of a few blows of a hammer, to hold said link 85 in place, the link in this case being made slightly narrower, so that the heads thereof will not bind in said recesses.

With this explanation of my invention its operation will be readily understood. When 90 desired to apply the same to a nut, the jaws of the wrench are first opened, the wrench set on the nut, and the wrench operated as usual. The movement of the lever part of the shank in the direction in which the nut is to be turned 95 will drive the movable jaw upward and firmly set the jaws on the nut, the hold on the nut becoming greater as the wrench is turned.

In the drawings, the under surface of the fixed or outer jaw is shown serrated; but this 100 construction of course is optional. In small wrenches constructed in accordance with my

invention the same may be manipulated with one hand, using the forefinger to lift the head to open the jaws and in starting the movable jaw to close upon the object to be engaged.

5 In larger wrenches one may have to manipulate the wrench with both hands.

Having thus fully described my invention, what I claim, and desire to secure by Letters Patent, is—

- 10 1. In the wrench, the combination of the shank, or handle, comprising two members, *b*, *b'*, pivotally united, the upper member being provided with a fixed jaw, and the lower member having a projecting lug, *c*, provided on its upper surface with a transverse slot enlarging downwardly into a parallel annular cavity or socket; the movable jaw, *a'*, slidably mounted on the member, *b*, and having on its under projecting surface, a transverse
- 15 slot enlarging upwardly into a parallel, annular cavity or socket; the connecting-link, *d*, having annular ends, or heads, adapted to be inserted in the sockets of the said lug, *c*, and movable jaw, *a'*; the heads of said connecting-link, *d*, being of lesser width than the length of their said sockets, and the edges of said sockets being slightly spread to retain the link in place, substantially as described.
- 20
- 25

2. In the wrench, the combination of the shank, or handle, comprising two members, *b*, *b'*, pivotally united, the upper member being provided with a fixed jaw, and the lower member having a projecting lug, *c*, provided on its upper surface with a transverse slot enlarging downwardly into a parallel annular cavity or socket; the movable jaw, *a'*, slidably mounted on the member, *b*, and having on its under projecting surface, a transverse slot enlarging upwardly into a parallel, annular cavity, or socket; the connecting-link, *d*, having annular ends, or heads, adapted to be inserted in the sockets of the said lug, *c*, and movable jaw, *a'*; the heads of said connecting-link, *d*, being of lesser width than the length of their said sockets, and the edges of said sockets being slightly spread to retain the link in place, substantially as described.

In testimony whereof I have hereunto subscribed my signature, this 13th day of November, 1899, in the presence of two witnesses.

WILLIAM H. PETERS.
